UNITED STATES PATENT OFFICE.

ALFRED G. PECK, OF BELLWOOD, NEBRASKA.

ROOF JACK.

Application filed November 10, 1924. Serial No. 743,935.

The invention relates to roof jacks, and has for its object to provide a device of this character, which is safe, simple in construction and may be easily and quickly placed 5 on a roof, no matter what the angle thereof, and forms a base for temporary scaffolding disposed on the roof while the roof is being repaired, painted or the like, and particularly when the roof is being shingled.

10 A further object is to provide a roof jack comprising a bar having plates secured to the under side thereof, which plates are provided with acutely angled prongs adapted to imbed in the roof and hold the bar in position. Also to provide the upper side of the 15 bar with a hinged member adapted to be engaged by a board, which hinged member has hingedly connected thereto adjacent its outer end a brace, which extends towards the upper side of the bar and terminates in a a hinged plate through which a securing bolt passes, which bolt also passes through the bar.

20 A further object is to provide adjusting 25 means comprising a plurality of apertures through the bar and forming means whereby the hinged member may be adjusted to various angled positions in relation to the bar, according to the pitch of the roof. Also to 30 provide the hinged member with a hook at its outer end adapted to hook over the upper edge of a board and prevent upward displacement of the board.

With the above and other objects in view 35 the invention resides in the combination and arrangement of parts as hereinafter set forth, shown in the drawing, described and claimed, it being understood that changes in the precise embodiment of the invention may 40 be made within the scope of what is claimed without departing from the spirit of the invention.

In the drawing:—

45 Figure 1 is a perspective view of a portion of a roof showing a pair of jacks applied thereto.

Figure 2 is a vertical transverse sectional view through a portion of the roof showing one of the jacks in side elevation.

50 Referring to the drawing, the numeral 1 designates an inclined roof of a barn, house or other type of building, and 2 the spaced jacks disposed on the outer side thereof. Each jack comprises an elongated bar 3 to the under side of which bar is secured adjacent its ends by means of rivets 4, which

however may be bolts if desired, plates 5. The plates 5 are provided with downwardly extending acutely angled prongs 6, which prongs are forced into the outer side of the 60 roof 1 when the bar is placed in position on the roof. It will be seen that the prongs 6 will positively hold the bar against longitudinal movement in the direction of the arrow a. Secured to the upper side of the 65 bar 3 at its upper end by means of the rivets 4 is a plate 7, and to which plate is hingedly connected at 8 an outwardly extending bar 9, which bar 9 is adapted to be disposed at a right angle to the roof 1, and by being 70 hinged the bar may vary in relation to the bar 3 and the pitch of the roof, thereby allowing the same to be accurately positioned at a right angle to the roof. The hinged bar 9 at its outer end terminates in a hook 75 10, which hooks over the outer edge 11 of the board 12, and prevents outward displacement or slipping of the board 12, and at the same time the bar 9 forms a brace for 80 holding the board 12 in position, and on which board a workman stands while shingling or repairing a roof.

The hinged bar 9 is provided with a hinged brace 13 connected hingedly at 14 to the outer end thereof, and which brace extends downwardly and inwardly towards the outer face of the main bar 3, and is hingedly connected at 15 to a plate 16, which rests on the outer face of the bar 3 and is secured thereto by means of the bolt 17, which passes through the plate 16 and one of a plurality of apertures 18 in the bar 3, therefore it will be seen that the hinged bar 9 is thoroughly braced and the angle of the hinged bar 9 in relation to the roof 1 90 may be easily and quickly adjusted according to the pitch of the roof. In practice any number of roof jacks may be used, and for purposes of illustration two are shown 95 in Figure 1.

100 From the above it will be seen that a roof jack is provided which is simple in construction, and one wherein the board supporting arms may be easily and quickly adjusted to various angles in relation to the roof, and when not in use, the jacks may be formed into a compact package for storage purposes, or for shipping purposes, by simply removing the bolt 17 and allowing the hinged member 9 to move into engagement 105 with the outer face of the bar 3, at which time the brace 13 and plate 16 will be in 110

close engagement with the outer face of the bar.

The invention having been set forth what is claimed as new and useful is:—

- 5 A roof jack comprising an elongated bar, plates secured to the under side of said bar at its ends and in spaced relation to each other, acutely angled prongs carried by said plates and adapted to imbed in a roof, a 10 plate secured to the upper side of said bar adjacent its upper end, a second bar hingedly connected to the inner end of said last named plate and adapted to receive thereon a board, a hooked member carried by the 15 outer end of the second bar and adapted to hook over the outer edge of the board and hold the board in engagement with the

plate secured to the upper side of the bar and against outward movement, a brace hingedly connected to the hinged bar adjacent its outer end and extending towards the upper side of the first mentioned bar, a plate hingedly connected to the brace, engaging the upper face of the first mentioned bar and a bolt extending through one of a plurality of apertures in the first mentioned bar and through said last named plate and a head carried by the bolt and engaging the under side of the bar between the spaced plates. 25 30

In testimony whereof I affix my signature.

ALFRED G. PECK.
